(57) **CLAIM**

The ornamental design for a power heat sink with imbedded fly cut heat pipes, as shown and described.

DESCRIPTION

FIG. 1 is a top perspective view of a power heat sink with imbedded fly cut heat pipes showing our new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is an additional bottom perspective view thereof; and,

FIG. 10 is a disassembled view corresponding to FIG. 9. The broken line showing on the drawing disclosure is for illustrative purposes only and forms no part of the claimed design.
